MAXIMILIAN MATHIAS, OF BERLIN, GERMANY, ASSIGNOR TO SIEMENS & HALSKE AKTIENGESELLSCHAFT, WERNERWERK, OF SIEMENSSTADT, NEAR BERLIN, GERMANY.

AUTOMATIC TELEPHONE-SWITCHING SYSTEM.

Application filed December 5, 1925, Serial No. 73,347, and in Germany January 22, 1925.

The present invention relates, broadly stated, to a circuit arrangement for automatic telephone systems with main and sub-exchanges located in tandem, in which, when 5 connections are set up over several sub-exchanges, the trunk lines and connecting devices located beyond the wanted subscriber's exchange are rendered available for other calls.

More particularly, the trunk line used for connecting the main exchange with the nearest serially located sub-exchange is rendered available for other calls when a train of impulses transmitted from a calling substation 15 has indicated that the connection is to be extended to one of the serially located sub-exchanges.

The drawings show by way of example, one method of carrying out the invention, all 20 those parts being omitted that are not required for explaining the essence of the invention.

Figure 1 shows diagrammatically the arrangement of the connecting devices for a 25 telephone system comprising a main exchange HA and two sub-exchanges, namely the sub-exchange UA and the intermediate exchange ZA.

Figure 2 illustrates more detailed the 30 method of setting up a connection.

To a main exchange HA is connected an intermediate exchange ZA and to the latter is connected a sub-exchange UA. The subscribers in the different exchanges are designated by Te 3200 and Te 3211 in the sub-exchange, by Te 3300 and Te 3311 in the intermediate exchange and by Te 4411 in the main exchange. Calls originated in the sub-exchange UA and in the intermediate exchange ZA always pass over the switch I.GW in the main exchange. These calls may be local calls or calls from one sub-exchange to the other or to the main exchange. The switch I.GW is again released when the 45 designation is given that either the intermediate exchange or the sub-exchange is wanted. For example a call from the subscriber Te 3200 (see Figure 1) of the sub-exchange UA to the subscriber Te 3311 of the intermediate exchange ZA passes over the two preselectors I.VW and II.VW, repeater Ue and its associated auxiliary register switch MS, trunk line VL, repeater Ue 1 and its associated register switch MS1, intermediate

switch ZW, trunk line VL 1, trunk line VL 55 2 and I.GW in the main exchange HA. The switch I.GW in the main exchange as well as the auxiliary register switches MS and MS1 are positioned by the first train of impulses. According to the invention, in the 60 manner hereafter described, the trunk line VL 1 is interrupted by the operation of the register switch MS1, hence the second train of impulses can not reach the I.GW in the main exchange, but this train positions the 65 register again, causing the intermediate switch ZW to seize an idle trunk line VL 3 leading to the desired exchange. The other trains of impulses required for reaching the wanted subscriber operate in known manner 70 the final selector LW, which is reached over the trunk line VL 3. If the subscriber Te 3200 wishes to make a local call, for example to the subscriber Te 3211, the second train of impulses operates the register MS and the 75 register causes the II.VW to move onto another row of contacts, whereupon the call to the wanted subscriber is set up over the trunk line connected to that row of contacts, for example over VL 4 and the final selector 80 LW. Similarly, when the subscriber Te 3300 of the intermediate exchange makes a local call to the subscriber Te 3311 or makes a call to the subscriber Te 3211 of the sub-exchange, after the connection has been 85 switched over to another row of contacts at II.VW in response to the setting of the auxiliary register switch MS2, the call is set up over the trunk line VL 5, II.GW in the intermediate exchange and the final selector 90 LW in the sub-exchange.

The circuit arrangement according to the invention will now be described with reference to the Figure 2, which shows the circuits more fully. By way of example it will 95 be assumed that the subscriber Te 3200 of the subexchange UA wishes to set up a call to the subscriber Te 3311 of the intermediate exchange ZA. When he removes his receiver in order to set up the connection, the preselectors I.VW and II.VW are started up in known manner, and after they have been positioned onto an idle trunk line, for example VL, the connection from the calling subscriber's station is switched through 100 the bridging relays A and B of the repeater Ue. The relays A and B are operated as well as the relay C 1, which ener-

gizes over the lead c . The circuit for the relay C 1 extends over: ground, battery, the two windings of T, wiper of I.VW and of II.VW, test lead c , winding I of the relay 5 C 1, off-normal contact k ground. In order to maintain itself energized after the off-normal contact k has been opened, the relay C 1 locks itself over its contact 1 $c1$. It also closes the following circuit over its contact 10 2 $c1$: ground, contact 2 $c1$, contact 3 a , winding of V 2 and of V 1, battery, ground. The relay A has opened its contact 3 a and has closed its contact 5 a . Thereby the short circuit is removed from the second winding 15 of the relay C 1 and the relay V 2 is short circuited. The relay A has also opened its contact 4 a . Furthermore, the relay C 1 has closed its contacts 6 $c1$ and 7 $c1$. Over the latter the following circuit is established: 20 ground, front contact 7 $c1$, test lead c' , winding I of C 2, off-normal contact 8 k , battery, ground. The relay C 2 is operated in this circuit and locks itself over its contact 9 $c2$ and its second winding. Furthermore, the relay C 2 at its contact 10 $c2$ 25 closes a circuit for the rotary magnet D of the intermediate switch ZW as follows: ground, double front contact 10 $c2$, back contact 11 p , rotary magnet D, relay interrupter RU, battery, ground. The intermediate switch ZW rotates its wipers 12, 13, 14, 15, until they encounter an idle line, for example VL 1, leading to the main exchange HA. The test relay P belonging to this line 30 is then energized in the following circuit: ground, double front contact 10 $c2$, windings II and I of P, back contact 16 $u2$, wiper 14, test lead c'' , winding of C 3, battery, ground. The relay P, by opening its contact 11 p , disconnects the rotary magnet D, and by closing its contact 17 p , it short circuits its second winding. Furthermore, by closing its contacts 60 p and 61 p , the relay P switches through the two talking 35 conductors of VL. Over a branch of the just mentioned test circuit and in parallel with relay C 3 an energizing circuit is also established for the relay S over the back contact 18 $v3$. The relay S opens its contact 19 s and interrupts the test circuit for the subscriber Te 3300 at the intermediate exchange, so he can not take the switch I.GW at the main exchange into use during the setting up of the connection. 40 The calling subscriber now transmits the first train of impulses, namely the number 3, which is the first digit of the wanted subscriber's number. Thereby the impulse relay A at the repeater Ue is made to de-energize three times in rapid succession. This causes the contact 4 a to be closed three times to transmit three current impulses over the upper lead of the line VL to the impulse relay A 1 at the repeater Ue 1, which circuit 45 may be traced as follows: ground, contact 4 a , front contact 6 $c1$, upper line conductor, back contact 20 f , winding of A 1, battery, ground. Each time the relay A 1 is energized, the following circuit is established for the rotary magnet Dm of the auxiliary register switch MS 1; ground, battery, rotary magnet Dm, contact 21 $a1$, ground. The wiper 22 of the auxiliary switch MS 1 advances a number of steps corresponding to the number of impulses transmitted. 50 These impulses, transmitted by the calling subscriber are repeated in a known manner from the bridging relay A 1 to the bridging relay of I.GW in the main exchange HA, whereby that switch is positioned. The transmitted impulses also operate the auxiliary register switch MS associated with the repeater Ue and cause it to move on. Although it is not shown in the drawing how the auxiliary switch MS is advanced by the 55 impulses, it will be understood that the circuits may be similar to those shown in connection with switch MS1. In the repeater Ue, the contact 5 a of relay A was opened when the relay A was released and it caused the short circuit to be removed from the relay V 2. Hence the relay V 2 operates, and by closing its contact 23 $v2$ it establishes the following circuit for the relay B 1 of the repeater Ue 1: ground, battery, front contact 23 $v2$, lower line conductor, back contact 24 f , winding of B 1, ground. The relay B 1 operates and, by opening its contact 25 $b1$, it prevents the circuit of the relay F being prematurely established. After the transmission of the first train of impulses, the wiper 22 of MS 1 stands on the contact 27. Thereby the following circuit is completed: ground, back contact 26 $a1$, back contact 25 $b1$, wiper 22, contact 27, winding I of the relay U 2, battery, ground. The relay U 2 operates and by opening the contact 28 $u2$ it removes the short circuit from its second winding. The relay U 2 by 60 opening its contact 16 $u2$ interrupts the test circuit of the line VL 1, and by closing its contact 29 $u2$ it switches the test circuit over to the other test wiper 15 of the intermediate switch ZW. The relay U 2 also opens its contact 30 $u2$ and so interrupts the upper line conductor of the trunk line VL. 65 The next train of impulses (the second digit 3 of the wanted subscriber's number) only operate the two auxiliary switches MS located in the repeater Ue and MS 1 in the repeater Ue 1. The selector I.GW at the main exchange can not be operated by the second train of impulses, because the impulse conductor is severed by the open contact 30 $u2$. The transmitted train of impulses again advance the wiper 31 of the auxiliary switch MS and the wiper 22 of the auxiliary switch MS 1 by three steps. Thereby nothing 70 happens at the auxiliary switch MS, but at 75 80 85 90 95 100 105 110 115 120 125 130

the auxiliary switch MS 1 the relay F is energized in the following circuit: ground, back contact 26 *a*1, back contact 25 *b*1, wiper 22, contact 32, winding of F, battery, ground. Relay F opens its contacts 20 *f* and 24 *f*, disconnecting the bridging relays A 1 and B 1. F also switches through the upper line conductor of the trunk line VL by closing its contact 33 *f*. The relay U 2 as will be remembered locked itself over its second winding and keeps contact 30 *u*2 closed. By opening its contact 16 *u*2, the circuit of relay P is interrupted, whereupon relay P deenergizes, closing the contact 11 *p* and again connecting the rotary magnet of the intermediate switch ZW to the relay interrupter RU. The switch ZW now rotates its wipers until they reach an idle line in the second contact row 63 (see Figure 1), to which the lines going to the intermediate exchange are connected. Thereupon the following circuit is established: ground, double front contact 10 *c*2, windings II and I of P, front contact 29 *u*2, wiper 15, test lead 25 *d*, winding of relay C 4, battery, ground. The wipers 12, 13, 15 now stand on the contacts 34, 35, 36. The calling subscriber now transmits the last two trains of impulses corresponding to the number 11. Thereby the 30 bridging relays A 2 and B 2 of the final selector LW are operated in known manner and the switch is positioned on the line of the wanted subscriber Te 3311. The wanted subscriber is then signalled as usual. When 35 he answers the call the setting up of the connection is completed. When the subscribers restore their receivers, the connection is released in known manner and all the devices used for setting up the call 40 are returned to their normal position.

When the calling subscriber Te 3200 wishes to set up a call to a subscriber belonging to his own exchange UA, for example the subscriber Te 3211, the following 45 operations have to be considered: The first train of impulses passes over the repeaters Ue and Ue 1, the auxiliary switches MS and MS 1 to the first group selector at the main exchange HA in the manner described for 50 the previous connection. After the first train of impulses, the line to the main exchange is interrupted by the energizing of U 2. The second train of impulses (second digit 2 of the wanted number) advances the 55 wipers 31 and 22 of the auxiliary switches MS and MS 1 by two steps. Thereby the relay F is energized over the auxiliary switch MS 1, and the relay opens its contacts 20 *f* and 24 *f* to disconnect the bridging relays A 1 and B 1 of the repeater Ue 1. The 60 second train of impulses positions the wiper 31 of the auxiliary switch MS of the repeater Ue on the contact 37, thereby completing the following circuit for relay U: ground, wiper 31, contact 37, winding of U, battery, ground. Relay U operates and by closing its contact 38 *u*, establishes the following circuit for the relay U 1 shown in the drawing at the secondary preselector I. V.W.: ground, winding of U 1, wiper 39 of the second preselector II.VW, contact 40, line lead *d*', front contact 38 *u*, battery, ground. The relay U 1 energizes in this circuit and closes its contact 41 *u*1, thereby interrupting the test conductor *c*. The closing of the contact 41 *u*1 also in known manner connects the rotary magnet of II.VW to the interrupter again. The second preselector rotates its wipers and hunts for an idle line in the second contact row 64 (see Figure 1), containing the lines leading to the local exchange. When an idle line is found, the wipers stand on the contacts 42, 43, 44. The following circuit is formed over the wiper 39: ground, winding of U 1, wiper 39, contact 44, line lead *d*''', winding of C 6, earth. The succeeding trains of impulses operate the bridging relays A 3 and B 3 of the final selector LW 1 in known manner, and cause the switch to be positioned onto the line of the wanted subscriber Te 3211.

The manner of setting up a call from the subscriber Te 3300 of the intermediate exchange ZA to the subscriber Te 3311 of the same exchange, will now be described. When the first and second preselectors have been positioned, the following circuit is established for the winding I of the relay C 5: ground, battery, windings of test relay T' and test wiper of the first preselector, contact 51 *u*4, test wiper of the second preselector, contact 19 *S*, winding of relay C⁵, off normal contact K 1, to ground. C 5 at its contact 45 *c*5 closes a locking circuit for itself independent of off normal contact K 1. At its contact 46 *c*5, the relay C 5 closes a circuit for the relay V 3. V 3 closes its contact 47 *v*3, thereby disconnecting the relay S and short circuiting relay P in order to prevent the sub-exchange UA taking into use the first group selector I.GW at the main exchange. The bridging relays A 4 and B 4 are operated over the subscriber's loop. The first train of impulses positions the auxiliary switch MS 2 and the first group selector I.GW at the main exchange HA in accordance with the selected number 3 (the first digit of the selected line). The second train of impulses (second digit 3 of the selected line) positions the wiper 48 of the auxiliary switch MS 2 onto the contact 49. Thereby the following circuit is established for the relay U 3: ground, wiper 48, contact 49, winding of U 3, battery, ground. The relay U 3 closes its contact 50 *u*3 located in the circuit of the fourth wiper of the second preselector and establishes a circuit for the relay U 4. The latter closes its contact 51 *u*4, thereby effecting a switching over to the other contact row 66 of the second preselector.

1. In a telephone system, an automatic main exchange, accessible over a common trunk line to a plurality of tributary automatic sub-exchanges located serially with respect to each other, calling and called substations in said exchanges, switching means in said tributary exchanges for automatically seizing said common trunk line upon a substation initiating a call, and substation controlled means for releasing said switching means from connection with said common trunk line and rendering said trunk line available, if said connection initiated by said calling station is to be extended to one of said tributary exchanges.

2. In a telephone system, an automatic main exchange, accessible over a common trunk line to a plurality of tributary automatic sub-exchanges located serially with respect to each other, other trunk lines connecting said tributary exchanges, calling and called substations in said exchanges, switching means in said tributary exchanges for automatically engaging said common trunk line upon a substation initiating a call, and substation controlled means for releasing said switching means from engagement with said common trunk line and for re-operating said switching means into engagement with one of said other trunk lines if said connection initiated by said calling station is to be extended to one of said tributary exchanges.

3. In a telephone system, an automatic main exchange, accessible over a common trunk line to a plurality of tributary automatic sub-exchanges located serially with respect to each other, calling and called substations in said tributary exchanges, switching means in said tributary exchanges for automatically extending the talking conductors of a calling substation to said common trunk line, other trunk lines, means for in-

terrupting the extended connection, and means for automatically operating said switching means to connect said calling substation to one of said other trunk lines if said connection initiated at said calling station is to be extended to one of said tributary exchanges.

4. In a telephone system, an automatic main exchange, accessible over a common trunk line to a plurality of serially located tributary automatic sub-exchanges, calling and called substations provided with sending devices, switching means in said exchanges susceptible to current impulses generated at said sending devices under subscriber control, for extending a connection from a calling to a called station, and automatic non-numerical switches controlled by said switching means for extending the talking conductors of a calling substation initially to said common trunk line and for then re-operating and extending said calling station to another trunk line if the impulses transmitted from said calling station signify that the connection is to be extended to one of the tributary exchanges.

5. In an automatic telephone system, a main exchange accessible over a common trunk line to a plurality of tributary exchanges, other trunk lines connecting said tributary exchanges, said trunk lines terminating in an automatic non-numerical switch, calling and called substations provided with impulse sending devices, means effective upon the initiation of a call at a calling station for operating said non-numerical switch to engage said common trunk line, and means responsive to the impulses transmitted at said calling station for re-operating said non-numerical switch to engage one of the other trunk lines if the connection is to be extended to one of said tributary exchanges.

6. In an automatic telephone system, a main exchange accessible over a common trunk line to a plurality of tributary exchanges, other trunk lines connecting said tributary exchanges, said trunk lines terminating in an automatic non-numerical switch associated with a repeater, a numerical switching device individual to said repeater and controlling said non-numerical switch, calling and called substations provided with impulse sending devices, means effective upon the initiation of a call at a calling station for seizing said repeater and for automatically actuating said non-numerical switch to engage said common trunk line, means responsive to the impulses transmitted at said calling station for operating said numerical switching device, and means actuated by said numerical switching device for re-operating said non-numerical switch to engage one of the other trunk lines if the impulses transmitted from said calling station

signify that the connection is to be extended to one of the tributary exchanges.

7. In an automatic telephone system, a plurality of exchanges, trunk lines connecting said exchanges, said trunk lines arranged in groups accessible to a non-numerical switch, calling and called lines provided with impulse sending devices, means effective upon the initiation of a call at a calling station for actuating said non-numerical switch to engage the first idle trunk line available in a certain group, and switching means responsive to the impulses transmitted at the calling station for re-actuating said non-numerical switch to select a trunk line within another group.

8. In an automatic telephone system, a plurality of exchanges, trunk lines connecting said exchanges, said trunk lines arranged in groups accessible to a non-numerical switch, calling and called lines provided with impulse sending devices, means effective upon the initiation of a call at a calling station for actuating said non-numerical switch to engage the first idle trunk line available in a certain group, and switching means responsive to the impulses transmitted at the calling station for re-actuating said non-numerical switch to select a trunk line within another group, said re-routing of a partly established connection being determined by the first train of impulses transmitted at the calling station.

9. In an automatic telephone system, a plurality of exchanges, trunk lines connecting said exchanges, said trunk lines arranged in groups accessible to a non-numerical switch, calling and called lines provided with impulse sending devices, means effective upon the initiation of a call at a calling station for actuating said non-numerical switch to engage the first idle trunk line available in a certain group, switching means responsive to the impulses transmitted at the calling station for re-actuating said non-numerical switch to select a trunk line within another group, said re-routing of a partly established connection being determined by the first train of impulses transmitted at the calling station, and effective only if the impulses signify that the connection is to be extended to a wanted substation within said other group.

10. In an automatic telephone system, calling and called substations provided with impulse sending devices, trunk lines leading in a first traffic direction and trunk lines leading in a second traffic direction, said trunk lines arranged in groups accessible to an automatic non-numerical switch, means effective upon the initiation of a call at a calling sub-station for automatically actuating said non-numerical switch to select an idle trunk line within said first group, and means individual to said selected trunk line and re-

sponsive to directive impulses generated at the calling station for re-operating said non-numerical switch to select a trunk line within said second group.

11. In an automatic telephone system, calling and called substations provided with impulse sending devices, trunk lines leading in a first traffic direction and trunk lines leading in a second traffic direction, said trunk lines arranged in groups accessible to an automatic non-numerical switch, means effective upon the initiation of a call at a calling sub-station for automatically actuating said non-numerical switch to select an idle trunk line within said first group, and means individual to said selected trunk line and responsive to directive impulses generated at the calling station for re-operating said non-numerical switch to select a trunk line within said second group, said rerouting of a partly established connection being determined by the second train of impulses transmitted at the calling station.

12. In an automatic telephone system, calling and called substations provided with impulse sending devices, trunk lines leading in a first traffic direction and trunk lines leading in a second traffic direction, said trunk lines arranged in groups accessible to an automatic non-numerical switch, means effective upon the initiation of a call at a calling sub-station for automatically actuating said non-numerical switch to select an idle trunk line within said first group, means individual to said selected trunk line and responsive to directive impulses generated at the calling station for re-operating said non-numerical switch to select a trunk line within said second group, said re-routing of a partly established connection being determined by the second train of impulses transmitted at the calling station, and effective only if the impulses signify that the connection is to be extended in said second traffic direction.

13. In an automatic telephone system, calling and called substations provided with impulse sending devices, two groups of trunk lines accessible to a first non-numerical switch and leading in a first and second traffic direction, the trunk lines within the first group terminating in a second non-numerical switch having access to two additional groups of trunk lines leading in a third and fourth traffic direction, means effective upon the initiation of a call at a calling station for operating said first and said second switch into engagement with idle trunk lines in said first and said third group, respectively, and numerical switching means individual to the selected trunk line of the first group and responsive to directive trains of impulses transmitted at the calling station for re-operating said first switch to engage a trunk line within said second group.

14. In an automatic telephone system, call-

- ing and called substations provided with impulse sending devices, two groups of trunk lines accessible to a first non-numerical switch and leading in a first and second traffic direction, the trunk lines within the first group terminating in a second non-numerical switch having access to two additional groups of trunk lines leading in a third and fourth traffic direction; means effective upon the initiation of a call at a calling station for operating said first and said second switch into engagement with idle trunk lines in said first and said third group, respectively, and numerical switching means individual to the selected trunk line of the first group and responsive to directive trains of impulses transmitted at the calling station for re-operating said first switch to engage a trunk line within said second group, said re-routing of a partly established connection being determined by the second train of impulses transmitted at the calling station.
15. In an automatic telephone system, calling and called substations provided with impulse sending devices, two groups of trunk lines accessible to a first non-numerical switch and leading in a first and second traffic direction, the trunk lines within the first group terminating in a second non-numerical switch having access to two additional groups of trunk lines leading in a third and fourth traffic direction; means effective upon the initiation of a call at a calling station for operating said first and said second switch into engagement with idle trunk lines in said first and said third group, respectively, and numerical switching means individual to the selected trunk line of the first group and responsive to directive trains of impulses transmitted at the calling station for re-operating said first switch to engage a trunk line within said second group, and effective only if said second train of impulses signifies that the connection is to be extended in said second traffic direction.
16. In an automatic telephone system, calling and called substations provided with impulse sending devices, two groups of trunk lines accessible to a first non-numerical switch and leading in a first and second traffic direction, the trunk lines within the first group terminating in a second non-numerical switch having access to two additional groups of trunk lines leading in a third and fourth traffic direction; means effective upon the initiation of a call at a calling station for operating said first and said second switch into engagement with idle trunk lines in said first and said third group, respectively; and numerical switching means individual to the selected trunk line of the first group and responsive to directive trains of impulses transmitted at the calling station for re-operating said second switch to engage a trunk line within said fourth group.
17. In an automatic telephone system, calling and called substations provided with impulse sending devices, two groups of trunk lines accessible to a first non-numerical switch and leading in a first and second traffic direction, the trunk lines within the first group terminating in a second non-numerical switch having access to two additional groups of trunk lines leading in a third and fourth traffic direction; means effective upon the initiation of a call at a calling station for operating said first and said second switch into engagement with idle trunk lines in said first and said third group, respectively, and numerical switching means individual to the selected trunk line of the first group and responsive to directive trains of impulses transmitted at the calling station for re-operating said second switch to engage a trunk line within said fourth group, said re-routing of a partly established connection being determined by the first train of impulses transmitted at the calling station.
18. In an automatic telephone system, calling and called substations provided with impulse sending devices, two groups of trunk lines accessible to a first non-numerical switch and leading in a first and second traffic direction, the trunk lines within the first group terminating in a second non-numerical switch having access to two additional groups of trunk lines leading in a third and fourth traffic direction; means effective upon the initiation of a call at a calling station for operating said first and said second switch into engagement with idle trunk lines in said first and said third group, respectively, and numerical switching means individual to the selected trunk line of the first group and responsive to directive trains of impulses transmitted at the calling station for re-operating said second switch to engage a trunk line within said fourth group, said re-routing of a partly established connection being determined by the first train of impulses transmitted at the calling station, and effective only if said first train of impulses signifies that the connection is to be extended in said fourth traffic direction.
19. In an automatic telephone system, calling and called stations provided with impulse sending devices, a first and a second exchange, a trunk line accessible to a first automatic non-numerical switch in said first exchange and terminating in a second automatic non-numerical switch in said second exchange and having access to groups of trunk lines leading in other traffic directions, said trunk line being provided at both ends with a numerical switching device individual thereto, means effective upon the initiation of a call at a substation for operating said first switch to select said trunk

- line, means effective upon seizure of said trunk line for operating said second switch to further extend the call, and means controlled by said numerical switching devices responding to the digits generated at said calling station, for re-operating said first or said second non-numerical switch to select a trunk line in other groups, depending upon the traffic direction signified by the digits.
- 5 20. In an automatic telephone system, calling and called stations provided with impulse sending devices, a first and a second exchange, a trunk line accessible to a first automatic non-numerical switch in said first exchange and terminating in a second automatic non-numerical switch in said second exchange and having access to groups of trunk lines leading in other traffic directions, said trunk line being provided at both ends 10 15 20 with a numerical switching device individual thereto, means effective upon the initiation of a call at a substation for operating said first switch to select said trunk line, means effective upon the seizure of said trunk line for operating said second switch to further extend the call, and means controlled by said numerical switching devices responding to the digits generated at said calling station, for reoperating said first or said second non-numerical switch to select a trunk line in other groups, depending upon the traffic direction signified by the digits, the re-operation of said first switch being determined by the second digit and the re-operation of said second switch being determined by the first digit.
- 25 30 35

In witness whereof, I hereunto subscribe my name this 26th day of October, A. D. 1925.

MAXIMILIAN MATHIAS.
